SKATE

Alexander L. Flamm, Fairfield, Conn.

Application November 17, 1937, Serial No. 175,094

5 Claims. (Cl. 280—11.19)

This invention relates to new and useful improvements in skates and has particular relation to roller skates.

The objects and advantages of the invention will become apparent from a consideration of the following detailed description taken in connection with the accompanying drawings wherein satisfactory embodiments of the invention are shown. However, it is to be understood that the invention is not limited to the details disclosed but includes all such variations and modifications as fall within the spirit of the invention and the scope of the appended claims.

In the drawings:

Fig. 1 is a side elevational view of my improved skate:

Fig. 2 is a transverse sectional view therethrough taken as along the line 2-2 of Fig. 1;

Fig. 3 is a bottom plan view showing a slight modification;

Fig. 3; Fig. 5 is a longitudinal sectional view of the
Fig. 4 is a rear elevational view of the slate of
but the views being on a larger scale;

Fig. 6 is a view showing an adjusting tool or
key to be used in adjusting the skates;

Fig. 7 is a perspective view of the skate of

Fig. 8 is a transverse sectional view as along the line 8-8 of Fig. 7;

Fig. 9 is a transverse sectional view taken as along the line 9—9 of Fig. 7;

Fig. 10 is an expanded view showing a wheel or roller mounting employed;

Fig. 12 is a similar view showing another part

Referring in detail to the drawings and at first more particularly to the form of the invention

more particularly to the form of the invention shown in Figs. 1 and 2 my improved skate includes a forward section generally designated 10 and a rearward section generally designated 11. These two sections are adjustable toward and from one another to shorten or increase the effective length of the body. Section 11 includes a bed portion 12 and an upstanding guard portion 13 shown as provided with slots 14 for the passage of securing straps or the like (not shown).

Also section 11 includes a depending skirt-like portion 15 which as shown best in Fig. 3, is generally circular, and to a large extent encloses a ground engaging roller or wheel 16. About por-

tion 15 is a relatively heavy bumper 17 of rubber or the like and such bumper covers a joint between the bed portion 12, guard portion 13 and skirt 15 as will later more fully appear. On the rear of section 11 there may be mounted a reflector or the like 18. While the mounting of wheel 16 will later be set forth in detail here it is noted that the same is mounted by blocks 19 of rubber or the like, the shaft of each wheel at 10 each side of said wheel being mounted between an upper and lower pair of such blocks.

an upper and lower pair of such blocks.

Forward section 10 includes a bed portion 20 above which extends an upwardly and rearwardly curved toe housing or guard portion 21 open at its rear side for the insertion of the toe of a shoe therein. Somewhat similar skirt-like guard portions 22 and 23 depend from the lower side of the bed portion 20 toward each side thereof and are connected at their forward ends whereby various parts located at the underside of the bed 20 (and now to be described) are enclosed at their sides and also at their forward ends. A bumper 24 of heavy rubber or the like encloses the joint between bed 20, housing 21 and skirt portions 22 and 23 and the details of such joint will later be given.

A bumper 25 also of heavy rubber or the like is carried vertically up the center of housing 21 and downwardly at the juncture of the housing 30 portions 22 and 23. At the forward side of housing portion 21 there is mounted a lens 26 in the rear of which there is located a bulb 27 wired to be energized from a battery 28 or from a generator 29 at the will of the user. With the battery 35 and generator both present the arrangement may be such that while the skater is not in motion the bulb 27 will be energized from the battery and when he is in motion the dynamo is directly energizing the bulb.

40 The periphery of a ground engaging wheel or roller 31 engages a pulley 30 on the shaft of the dynamo 29 and serves thereby to drive the generator while the skater is in motion. Wheel 31 is mounted on a shaft the ends of which are received between rubber or other cushioning blocks 19 as in the case of the wheel 16 on skate section 11 and the details of this mounting will later be given when specifically considering Figs. 10, 11 and 12.

50 In addition to the ground engaging wheel 31 the forward skate section 10 mounts a ground engaging wheel 32 arranged laterally and rearwardly of the wheel 31. Wheel 32 is of a diameter smaller than that of wheel 31 and comprises a balancing wheel only as it usually will be off

the ground while the skater is in motion and is, generally speaking, used only as a balancing medium while the wearer of the skates is standing but not in motion. This wheel 32 is mounted in the same manner as the other wheels and as above suggested the details of the mounting will later be given.

On its inner side the upper housing 21 is lined with leather or the like as at 33 in Fig. 2. Forward section 10 is provided with clamping means whereby the skate may be attached to the sole of a shoe and as here shown such clamping means includes a pair of clamping elements 34 extending through slots 35 in bed 20 and having their lower ends off-set and tapped for the reception of a transversely extending screw 36. Such screw toward its opposite ends is oppositely threaded whereby on turning of the screw in one direction the clamps are fed toward one another and on turning of the screw in the opposite direction the clamps are opened. The end 37 of the screw 36 is shaped to be received in a socket 38 in a key or tool 39 whereby the screw may be easily turned to adjust the clamps.

The skate of Figs. 3 and 4 is the same as that of Figs. 1 and 2 with the exception that in the skate 40 of Figs. 3 and 4 the forward and rearward sections 10 and 11 are adapted to be adjusted toward and from one another by the turning of a screw 41 extending longitudinally of the skate. Screw 41 includes an enlarged portion 42 abutting against a lug 43 carried by section 11 and the screw is threaded through a tapped lug 44 on the section 10. The end 45 of the screw is exposed at the rear of the skate and is shaped to be received in the socket 38 of tool 39 by means of which the screw may be turned in the desired direction for shortening and lengthening of the skate.

The mounting of the various rollers or wheels is shown in Figs. 10, 11 and 12. As shown in such figures the wheel designated 46 is mounted on a shaft 47 extending from opposite sides of the wheel. The ends of the shaft 47 are received in bushings 48 mounted in blocks 49 of rubber or other yielding material. While the blocks 49 are shown in one piece it will be apparent that they may each comprise a pair of parts, as upper and lower parts, as suggested in Figs. 1 through 4. Washers 50 may be interposed between the wheels and the bushing 48 if desired.

When the wheel, shaft, bushings and blocks are assembled into a unit they are then mounted in a housing including a lower part 51 and an upper part 52. Part 51 includes side walls 53 provided with opposed channels 54 and 55 open at their upper ends. The assembled unit may be slipped into place in the housing part 51 through the upper side thereof, the blocks 49 being received in the channels 54 and 55 which are of a depth to receive the blocks and have the wheels in place between the blocks. When the unit is in place in the part 51 the housing part 52 is applied and it includes an arcuate part 56 to extend over the upper side of the wheel and side lugs 57 to enter the upper ends of the channels 54 and 55 and to therein engage the upper edges of the blocks 49 to hold the blocks in place against the lower end walls 58 of such channels. Each housing part 51 includes lugs 59 by means of which the part is mounted in the skate as will later (when considering Figs. 5, 7, 8 and 9) appear.

Referring now to the form of the skate shown in Figs. 5, 7, 8 and 9 the same comprises a forward

section 60 and a rearward section 61. The latter section includes a bed 62 the forward portion of which is U-shaped in transverse section (see Fig. 8) including depending side flanges 63. Extending upwardly from the bed 62 is a rear wall 64 and about the same and depending therefrom and the bed is a skirt-like portion 65. Portion 65 may be attached in any desired manner but as here shown is welded or soldered to the portion 64 as at 66.

Mounted in the skirt-like portion 65 is a wheel 67 the same being mounted in a housing including the parts 51 and 52 above described. In Fig. 5 it will be noted that a cup or ring 65a is bent about the lugs 59 of part 51 and such part 65a abuts the lower edge of skirt 65 and such abutting portions may be riveted or otherwise secured together and the joint thus formed is covered by a bumper 68 of heavy rubber or the like. The top or cover housing part 52 has its lugs 57 entering the channels 54 and 55 of the part 51 and holding the rubber bearing blocks 49 in place and such part 52 is held in place by being engaged by the bed 62 as at 69 in Fig. 5.

Forward skate section 60 includes a bed 70 above the front end portion of which extends a curved guard 71 and below which extends a skirt portion 72. The adjacent edges of the portions 70, 71 and 72 abut as at 73 (Figs. 8 and 9) and are secured together as by rivets or the like 74. A bumper of rubber or the like 75 encloses the joint 73, while a similar rubber bumper 76 encloses the joint 77 between the two companion parts of the toe housing or guard 71.

Skirt 72 has pockets 78 and 79 opening through its under side and through the under open ends of which project the rollers 80 and 81. The pockets 78 and 79 receive the housing parts 51 and 52 and in the case of roller 80 the housing part 52 is held down in place since it is engaged by the depressed portion 82 of the bed 70. The upper housing part 52 associated with roller 81 is kept in place by means of a lug 83 lanced and pressed from the bed 62 and engaging the top portion of such part as shown best in Fig. 9. Housing parts 51 associated with rollers 80 and 81 are secured by portions 72a of the skirt or guard 72.

Sections 60 and 61 are adjustable toward and from one another on manipulation of a worm 84. Such worm passes through a lug 86 on section 60 and the worm is fixed to a lug 87 carried by section 61. The forward bed portion of section 60 is depressed to form a strap-like portion 88 (see Fig. 8) to extend beneath the forward portion of skate section 61 and section 60 has lugs 89 lanced and pressed therefrom to extend over the forward portion of the bed 62 of section 61. In this way the intermediate portions of the sections are held against any relative vertical movements but yet may have a telescopic movement. Obviously on turning of screw 84 in one direction the sections will be drawn toward one another to shorten the skate and on turning of the screw in the opposite direction the parts are forced from one another to lengthen the skate.

A shaft 90 extends transversely of the skate at the underside of section 60 and is mounted as by lugs 91 lanced and pressed from the bed 70. Shaft 90 carries a gear 92 held against casual backward movement by a pawl 93 and meshing with the shaft or screw 84 whereby on turning of shaft 90 the screw 84 is rotated. One end of shaft 90 is carried to an opening 94 in the skirt portion 72 and such end of the shaft is shaped

to be received in the socket 38 of tool 39 for turning of the shaft.

A reflector 95 may be mounted in the rear side of the skirt portion 65 and somewhat similarly a lens 76 is arranged in the forward side of the toe guard 71. In the rear of such lens is a bulb 97 connected as by wires 98 with a dynamo 99 the pulley 100 of which is engaged and driven by the periphery of the wheel 80. Obviously with this arrangement the bulb 97 will be energized only while the wheel 80 is in motion.

Having thus set forth the nature of my invention, what I claim is:

1. In a skate, a body including an upper surface, ground engaging rollers at the under side of said body, a guard secured to said body and depending at the lower side thereof, said guard comprising a hollow shell open at its upper side toward said body and having a roller receiving opening in its lower wall through which one of said rollers projects, a housing, bearing means in said housing in which said roller is mounted, and means mounting said housing in said guard adjacent said opening whereby the front and side walls of said guard enclose and conceal said housing, bearing means and a larger portion of said roller.

2. In a skate, a body including a platform-like portion, ground engaging rollers at the under side of said body, a shell-like guard member open at its upper side and including front, bottom and side walls, said guard having an opening in its bottom wall through which said roller projects, a second shell-like guard member open at its lower side and including front, top and side walls and open at its rear for the reception of the toe portion of a shoe, and means securing the upper

edge of said first mentioned guard and the lower edge of the second mentioned guard to the edge portions of said platform-like portion of the skate body.

5. The combination as in claim 2 including means enclosing and concealing the connections between said guards and the platform-like portion of said body, and said means including an outer heavy rubber bumper strip disposed about the front and sides of the skate.

10. 4. In a skate, a body, a roller at the lower side of said body, a shaft carrying said roller and projecting at each side thereof, bushings receiving the ends of said shaft, rubber blocks in which said bushings are embedded, a lower housing member including spaced side walls, vertically disposed channels in said walls and receiving said blocks with said roller projecting through the lower end of the housing, an upper housing member disposed over said lower housing member and held in relation thereto by engagement with the skate body, and projections on said upper housing member and entering said channels and maintaining said blocks in position therein.

15. 5. In a skate, a body including an upper platform-like surface, a shell-like guard open at its lower side and including front, top and side walls, said guard having its open lower side disposed against said body and having its rear side open to receive the toe of a shoe, a pair of clamps disposed on said body within said guard for clamping the sole of the toe portion of a shoe, and means to move said clamps toward and from one another for clamping and releasing the sole of a shoe.

ALEXANDER L. FLAMM.
